UNITED STATES PATENT OFFICE.

GEORGE D. GARVIE AND GEORGE WOOD, OF NEW YORK, N. Y.

COMBINED SEWING-MACHINE AND MUSICAL INSTRUMENT.

SPECIFICATION forming part of Letters Patent No. 267,874, dated November 21, 1882.

Application filed June 17, 1882. (No model.)

To all whom it may concern:

Be it known that we, GEORGE D. GARVIE and GEORGE WOOD, both residing in the city, county, and State of New York, have invented 5 certain new and useful Improvements in the Method of Uniting and Combining a Musical Instrument with a Sewing-Machine, of which the following is a specification.

The musical instrument we have chosen to 10 combine with a sewing-machine for the purpose of illustrating our invention is called an "organette," and the portion of the sewing-machine with which we combine the musical instrument is the usual cover-frame or cabinet 15 inclosing an ordinary sewing-machine.

The object of our invention is to utilize the motive power of the sewing-machine for the purpose of operating the organette or any other musical instrument of a similar kind.

20 The following is a full, accurate, and complete description of our improvements, reference being had to the accompanying drawing, in which the figure is a vertical section.

a is the driving-wheel of the sewing-machine; 25 *b*, the loose fly-wheel; *c*, the end of the bracket-arm; *d d*, the sewing-machine cover; *e*, the bellows for supplying air to the organ; *f f'*, a crank and pulley wheel which operates the bellows and propels the perforated sheet of 30 paper through that portion of the sewing-machine frame which is used as a music-box. *g g* is the box containing the reeds.

The construction and arrangement of this 35 music-box, in combination with a sewing-machine, is very simple and easily understood.

The fly-wheel *b* is provided with a rubber

band or roller, *s*, which, by means of the friction-clutch commonly used in sewing-machines, can be brought in contact with the crank and pulley wheel at pleasure when the sewing-machine is not in operation. The fly-wheel being 40 put in motion by the treadle of the sewing-machine, the crank and pulley wheel *f f'* is operated by frictional contact with the rubber-roller on the fly-wheel, and the bellows of the 45 musical instrument is operated by the crank, and the paper is put in motion and carried forward over the reeds of the musical box by the feed-roll *n'*, operated by the pulley-band *n*.

It will be seen that the sewing-machine cover 50 or music-box can be detached from and adjusted to the sewing-machine without disarranging the sewing mechanism in any particular.

The sewing-machine cover, which by the invention here described is transformed into a music-box, is made entirely independent of but adjustable to the sewing-machine in the manner described and shown.

Having thus described our invention, what 60 we desire to secure is—

A cover for a sewing-machine, provided with a musical instrument and means for transmitting motion from the shaft of the sewing-machine to the operating parts of the musical 65 instrument, substantially as described.

GEO. D. GARVIE.
GEO. WOOD.
